L. J. BLACK

SELF LUBRICATING CROSSHEAD

Filed June 9, 1923

I. J. Black ^{Inventor}
Frederick S. Hall
Attorney

UNITED STATES PATENT OFFICE.

LEE J. BLACK, OF BEAUMONT, TEXAS.

SELF-LUBRICATING CROSSHEAD.

Application filed June 9, 1923. Serial No. 644,423.

To all whom it may concern:

Be it known that I, LEE J. BLACK, a citizen of the United States, residing at Beaumont, in the county of Jefferson and State of Texas, have invented certain new and useful Improvements in Self-Lubricating Crossheads, of which the following is a specification.

This invention relates to the slush pumps 10 which are used with hydraulic rotary drilling mechanisms, and particularly to the cross heads thereof.

In all of the standard forms of slush pump known to me, the valve actuating 15 rocker arm is connected to the connecting rod extending between the pump piston and the steam piston by a cross head, the cross head being formed with two abutments spaced from each other and the rocker arm 20 having a pin or equivalent device extending into the space between said abutments so that as the pistons reciprocate the rocker arm will be oscillated to thereby actuate the steam valves. In none of the slush pumps 25 known to me is any special provision made for lubricating the pin and roller which is carried by the lower end of the rocker arm and which is disposed between and engages these abutments. This part of the mechanism, if it is oiled at all, is oiled by the ordinary oil can.

The general object of my invention is to provide means for automatically lubricating the roller and pin upon which it is mounted.

A further object is to provide a cross head having therein a reservoir, means being provided whereby oil may be conducted from the reservoir onto the roller to thus lubricate the bearing for the roller and the roller 40 itself and through the roller the opposing faces of the abutments.

A still further object is to provide a device of this character so constructed that upon the upward movement of the roller between the abutments lubricant will be positively discharged upon the roller.

Other objects have to do with the details of construction and arrangement of parts as will appear more fully hereinafter.

50 My invention is illustrated in the accompanying drawings, wherein:—

Figure 1 is a fragmentary side elevation of a cross head and rocker arm such as is used in slush pumps, the cross head being 55 partly broken away and the pin and roller being in section;

Figure 2 is a section on the line 2—2 of Figure 1;

Figure 3 is a fragmentary section on the same plane as Figure 1, but showing the 60 rocker arm oscillated and the manner in which the roller squeezes the wick.

Referring to these drawings, 10 designates the piston rod leading to the steam cylinder of a slush pump, and 11 designates the 65 piston rod leading to the pump cylinder, these piston rods having screw-threaded extremities, as at 12, engageable in the ends of an intermediate section or cross head 13. This cross head 13 has screw-threaded 70 apertures 14 in which the piston rods engage and is formed with downwardly extending abutments 15, these abutments being spaced from each other to provide a vertical passageway 16 between the abutments. The 75 cross head 13 is formed to provide a lubricant chamber 17, the cross head having an opening 18 in its top closed by a plug 19 whereby lubricating oil may be fed into the chamber 17. The bottom of the chamber is 80 formed with a passageway 20 extending downward and opening upon the upper face of the recess 16. The rocker arm 21 is of the usual type and mounted upon the shaft 22. This rocker arm is operatively connected by 85 means (not shown) to the valves of the steam dome. The lower end of the rocker arm is bifurcated to provide two parallel yoke portions 23 and through these portions passes the pin 24 which is headed at one end 90 and provided with a cotter pin 25 at the other. Mounted upon this pin 24 and rotatable thereon and disposed between the arms 23 is the roller 26 which is formed with radial apertures 27. Extending downward 95 through the aperture 20 is a wick 28, this wick being preferably folded upon itself and the bight being passed down through the aperture 27 and extended downward sufficiently so that it rests upon the outer face 100 of the roller 26 when the roller is in its lowest position in the guideway or passageway 16.

It will be seen that when the rocker arm moves to the right or to the left from the position shown in Figure 1, that the roller will move upward within the passageway 16 and will compress this wick and squeeze the oil therefrom and this will occur each time that the roller moves upward into the upper portion of the recess or passageway 16. The oil squeezed from the wick will pass

through the openings 27 to the surface of the pin 24 and will lubricate the surface of this pin and will also lubricate the surface of the rollers and these rollers in turn will 5 carry the oil to and apply it against the faces of the abutments so that the cross head will be automatically lubricated as the pump operates.

As illustrated in Figure 1, the cross head 10 is formed at its ends with the outwardly projecting portions 29 into which the screw-threaded ends of the piston rods 10 and 11 are screwed, and in order to hold these piston rods in place in the cross head and prevent 15 any accidental detachment of the piston rod, jam nuts 30 are applied to the screw-threaded portions of the piston rod and abutted against the ends of the screw-threaded portions 29.

20 The construction which I have described permits the ready detachment of the piston rods from the cross head in order to insert a new cross head or to disassemble the machine and, of course, permits as ready an assembly 25 of the machine. The lubrication is automatic and constant. One of the important advantages of this invention is that the guideway 16 between the abutments 15 is open at its lower end so that any mud, grit 30 or other foreign matter which might otherwise accumulate between these jaws or abutments 15 will automatically drop away from the roller on the downward stroke of the roller when at its lowest point or near the 35 center. Thus the space between the abutments and the roller itself are automatically cleaned.

I claim:—

1. In a structure of the character described, 40 a reciprocable element having opposed spaced abutments, an oscillatable element coacting therewith and having a member extending between said spaced abutments, the reciprocable element having rectilinear movement only and said member moving transversely between the abutments as the oscillatable element is oscillated, and means acting to lubricate said member as it moves transversely between said abutments 45 toward the reciprocable element.

2. In a structure of the character described, 55 a reciprocable element having opposed spaced abutments and an oscillatable element coacting therewith and having a member extending between said opposed abutments, the reciprocable member carrying a lubricating reservoir, and a wick extending through an opening in the reservoir from the reservoir to the member disposed 60 between said abutments.

3. In a structure of the character described, 65 a reciprocable element having opposed spaced abutments and an oscillatable element coacting therewith and having a pin extending between said opposed abutments,

a roller mounted upon said pin, the reciprocable member carrying a lubricant reservoir, and means for conveying lubricant from the reservoir to the exterior face of the roller.

4. In a structure of the character described, 70 a reciprocable element having opposed spaced abutments, an oscillatable element coacting therewith, a pin carried by the oscillatable element and extending between said abutments, a roller mounted upon 75 the pin and having radial openings, the reciprocable element being formed to provide a lubricant reservoir, and a wick extending from said reservoir into the space between said abutments and adapted to contact with 80 said roller.

5. In a structure of the character described, 85 a reciprocable element having opposed spaced abutments constituting vertical guides spaced from each other at their lower ends, an oscillatable element coacting therewith and having a pin extending between said abutments, a roller mounted upon the pin and provided with openings extending from the surface of the roller to said pin, the abutments being spaced from each other at their lower ends and there being an aperture leading from the reservoir opening upon the under face of the reservoir between said abutments, and a wick disposed 90 partially in the reservoir and extending out through said opening and extending downward toward and adapted to contact with 95 the face of the roller.

6. In a structure of the character described, 100 a reciprocable cross head formed to provide a reservoir and having below the reservoir two opposed spaced abutments, the abutments being separated at their lower ends, a rocker arm having a yoke embracing 105 said cross head and extending downward on each side of the abutments, a pin mounted upon the yoke and extending between said abutments, a roller loosely mounted upon the pin and having apertures extending through to the pin, the wall forming the bottom of the reservoir being apertured, and a wick disposed partially in said reservoir 110 and extending down through said aperture and being disposed to contact with the roller.

7. In a structure of the character described, 115 a reciprocable cross head chambered to provide a lubricant reservoir, the cross head below the lubricant reservoir being provided with two downwardly extending spaced abutments separated at their lower ends, the bottom of the reservoir between the upper ends of the said abutments being apertured and the reservoir having filling 120 means, a rocker arm bifurcated to provide a yoke embracing the cross head, a pin extending through the lower end of the yoke and extending between the abutments of the cross head, a roller loosely mounted upon 125 the pin and having apertures extending 130

through to the pin from the surface of the roller, and a wick of flexible material partially disposed within the reservoir and extending through said aperture in the bottom 5 thereof and extending downward into the space between the abutments, that portion of the wick disposed between the abutments being flexible whereby as the roller rises in the space between the abutments it may compress the wick to force the lubricant therefrom.

8. In a structure of the character described, a reciprocable element having opposed spaced abutments, an oscillatable element coacting therewith and having a mem-

ber extending between said spaced abutments, the reciprocable element having rectilinear movement only and said member moving transversely between the abutments as the oscillatable member is oscillated, and means acting to lubricate said member as it moves transversely between said abutments toward the reciprocable element and including a wick carried by the reciprocable element and extending toward said member and compressed by the member as the member moves transversely between the abutments toward the reciprocable member.

In testimony whereof I affix my signature.
LEE J. BLACK.
